BRACELET

Frances H. Fiely, 1448 John Glenn Road,
Dayton, Ohio 45410

Filed Oct. 22, 1965, Ser. No. 87,814

Term of patent 7 years

(Cl. D45—4)

FIG-1

FIG-2

FIG-3

FIG-4

FIG. 1 is a perspective view of a bracelet showing my new design, the broken line showing of the pencil being for illustrative purposes only;

FIG. 2 is a front elevation thereof;

FIG. 3 is a side elevation thereof; and

FIG. 4 is a top plan view thereof.

The dominant features of my design reside in the annular bracelet portion which is relatively thin and having parallel upper and lower surfaces with rounded side edges, and having mounted centrally thereon an integral upstanding truncated pyramid portion. The truncated portion has a circular cut out therethrough parallel to the width of the bracelet and intersecting the top surface of the truncated portion. The width of the truncated portion at its base as less than the width of the upper and lower surfaces of the bracelet portion.

I claim:

The ornamental design for a bracelet, substantially as shown and described.
